UNITED STATES PATENT OFFICE.

MARIANO P. SCARDINO AND PETER SCARDINO, OF BRYAN, TEXAS.

HALF-CAR UNLOADER.

1,235,386.

Specification of Letters Patent. Patented July 31, 1917.

Original application filed December 15, 1913, Serial No. 806,918. Divided and this application filed November 2, 1914. Serial No. 869,961.

To all whom it may concern:

Be it known that we, MARIANO P. SCARDINO and PETER SCARDINO, citizens of the United States, residing at Bryan, in the county of Brazos, State of Texas, have invented certain new and useful Improvements in Half-Car Unloaders; and we do hereby declare the following to be a full, clear, and exact description of the invention, such as will enable others skilled in the art to which it appertains to make and use the same.

This invention relates to the handling of material in bulk and has special reference to a device arranged to enable railroad cars such as are used for hauling coal, ore, and other like material to be unloaded by a single operation. The form of device here presented is divided out of our application, Serial No. 806,918 filed December 15, 1913, which application has matured into a Patent No. 1,128,258 which was issued Feb. 9, 1915.

The principal object of the invention is to improve and simplify the general construction of devices of this character.

A second object of the invention is to provide an improved apparatus for hoisting a car, moving the car off the track in a lateral direction when hoisted, and then dumping the car and replacing it upon the track.

A third object of the invention is to provide an improved means for controlling the hoisting and dumping operations of a device of the character described.

A fourth object of the invention is to provide an improved derrick or crane for accomplishing the objects hereinbefore set forth.

A still further object of the invention is to provide a portable crane arranged to accomplish the hoisting and overturning of a car in order to dump the same.

With the above and other objects in view the invention consists in general of certain novel details of construction and combination of parts hereinafter fully described, illustrated in the accompanying drawings, and specifically claimed.

In the accompanying drawings like char-

acters of reference indicate like parts in the several views, and

Figure 1 is a plan view of the device;

Fig. 2 is a side view of the same;

Fig. 3 is a detail plan view of the drum arrangement;

Fig. 4 is a front view of the device.

Referring more particularly to the drawings, 10 represents a frame which consists of the upright members or posts 11 which are connected at their tops in pairs by the transverse members 12 suitably braced together by braces 13. Rails 14 are located on the members 12 and on these rails is mounted a traveling crane comprising a girder 15 having at each end a carriage 16 provided with wheels 17 which run on the respective rails 14.

This frame 10 is placed so that a track 18 runs therethrough on which the car 19 to be operated upon is placed. In order that this car 19 may be raised, we have provided on the girder 15 a plurality of pulleys 20 from which extend cables 21, the said cables extending downwardly and around pulleys 22 and 23, and over a drum 26, the latter being revolvably mounted on a shaft 25 which is supported on a frame 24 and clutched thereto by means of a clutch 27. In order that the motion of this drum may be arrested after the clutch has been thrown out, we have provided a band brake 28 which is operated by means of a rod 29 and a lever 30. In order that the retrograde movement of this drum may be prevented, we have provided a ratchet wheel 31 on the end thereof, and a pawl 32 co-operating therewith, which pawl is operated by means of a rod 33, the latter being connected to a lever 34. The other ends of these cables 21 are connected to yokes 35 on the ends of the car by means of hooks 36.

In order that the car may be tilted after having been raised, we provide a cable 37 which winds on a pulley 38 on the girder 15 and thence around a drum 39 which is revolvble on a shaft 40 and is clutched thereto by means of a clutch 41. A brake 42 is provided by means of which the movement of the drum is controlled. This drum

has a ratchet 43 on the end thereof, which cooperates with a pawl 44 connected to a lever 45 to prevent the retrograde movement of the drum.

5 In order that the girder 15 may be drawn backwardly over the track, we have provided on one of the braces 13 at each end thereof a pulley 46 over which pulleys pass cables 47, the latter being wound upon a 10 drum 48 which is likewise clutched to a shaft 49 by a clutch 50 and the motion of which is controlled by a band brake 51 connected to a lever 52. The clutches 27, 41 and 51 are controlled by levers 53 operable on 15 quadrants 54 and connected to the said clutches by means of rods 55 and bell crank levers 56. In order that motion may be imparted to the drum 39, we have provided on the end of the shaft 40 a gear 57 which 20 meshes with a worm gear 58, the latter being driven by means of a motor 59, motion is transmitted from this shaft 40 to the shaft 49 by means of a chain 60 and from the shaft 49 to the shaft 25 by means of a 25 chain 61, the chains being located on the opposite ends of the respective shafts.

From the foregoing description it will be readily seen that we have provided a simple and efficient device for hoisting and dumping cars, and we have so constructed the device that the car will be hoisted, carried to a dumping position and then dumped and will then be returned to its position on the track.

30 35 While we have illustrated and described a particular embodiment of our invention, we do not wish to be limited to that particular embodiment as it is obvious that

numerous changes may be made in the details of construction thereof without departing from the spirit of the invention or exceeding the scope of the appended claim.

What is claimed is:—

In a half car unloader, the combination of a frame including uprights adapted to be arranged on each side of a track, transverse side bars connecting said uprights, braces extending between said side bars, parallel rails mounted upon and extending between said braces and running transversely of said track, a carriage mounted upon each of said rails, a girder extending between and secured to said carriages and provided with a pulley adjacent each end, the ends of said girder extending over and beyond said transverse bars, a guide roller depending from each end of said girder and engaging the exterior side of the adjacent transverse bar, pulleys carried by certain of said uprights, raising and tilting cables extending around certain of the last named pulleys and the pulleys on said girder and depending therefrom, a pair of spaced pulleys secured to one of said braces, cables secured to said carriages and extending around the pulleys secured to one of said braces and the other pulleys carried by said uprights, and means for actuating all of said cables.

In testimony whereof we affix our signatures, in the presence of two witnesses.

MARIANO P. SCARDINO.
PETER SCARDINO.
